UNITED STATES PATENT OFFICE.

JOSEPH B. LONG AND FRANK TODD, OF CHICAGO, ILLINOIS, ASSIGNEES, BY DIRECT AND MESNE ASSIGNMENTS, TO LONG MANUFACTURING COMPANY, OF CHICAGO, ILLINOIS, A CORPORATION.

RADIATOR FOR AUTOMOBILES.

964,799.

Specification of Letters Patent. Patented July 19, 1910.

Application filed May 22, 1909. Serial No. 497,887.

To all whom it may concern:

Be it known that we, JOSEPH B. LONG and FRANK TODD, citizens of the United States, residing at Chicago, in the county of Cook and State of Illinois, have invented certain new and useful Improvements in Radiators for Automobiles and for other Purposes, of which the following is a specification.

While the invention is above termed a radiator for automobiles, it is manifest that it may be used for other specific purposes in which a circulating medium passing through the apparatus is to be cooled, or to give out its heat to the surrounding atmosphere, and in this aspect or consideration of the device it may be used for heating the surrounding air of a room of a building, thus conserving the heat, instead of, as in the case of a radiator or cooler for automobiles, simply dissipating it in the outer air as the machine progresses. Efficiency, in the case of an automobile radiator, is, of course, the chief object aimed at, and other important objects are, to produce a radiator of substantial and durable construction, having the necessary strength, rigidity and durability, while at the same time requiring a minimum amount of sheet metal (usually copper) in its construction, thereby not only accomplishing a saving in the cost of the metal but confining the radiator as a whole to as light weight as is consistent with the necessary strength, durability and efficiency.

There is a familiar and popular type of radiator which is known as the "honey comb." These radiators have water tubes extending from the upper to the lower header and so spaced apart as to leave between them horizontal passages extending from front to back of the radiator, for permitting the passage of air as the machine progresses.

Another and very important object of the invention is to provide a radiator improved in its construction with respect to the facility with which one or more of the water tubes which may become leaky or damaged may be removed, repaired, and reversed, or a new tube or tubes substituted without disturbing the others, or disassembling substantially all

of the parts and rebuilding the entire radiator.

To these ends the invention consists in the features of novelty that are hereinafter described with reference to the accompanying drawings which are made a part of this specification and in which:

Figure 1 is a front elevation on a small scale of a radiator embodying the invention. Fig. 2 is a perspective view of a rectangular frame, hereinafter particularly described, which divides the radiator into a plurality of horizontal sections or divisions. Fig. 3 is a vertical section of a fragment of a radiator embodying the invention, about full size excepting that it is much enlarged and exaggerated in the matter of the thickness of the sheet-metal and excepting that an intermediate horizontal portion is broken away. Fig. 4 is a horizontal section of two of the water tubes and one of the intervening so-called channel sheets, the parts being shown on an enlarged scale so far as thickness or lateral horizontal extent is concerned. Fig. 5 is a perspective view of a fragment of one of the channel sheets. Fig. 6 is a diagrammatic view of a blank of which the channel sheets are formed. Fig. 7 is a perspective view of fragments of two of the water tubes and one of the channel sheets, said view showing, more particularly, the form and relative arrangement of the parts of the lock joints or lock seams by which adjacent water tubes are secured together.

The radiator has a suitable frame A, the shape or design of which is left to the choice of the builder or determined by the exigencies of individual cases. It has, also, upper and lower headers, or chambers, B and B' respectively, for receiving the water to be cooled as it comes from the water jacket of the engine, and for receiving it after it passes through the water tubes C and is thereby cooled, after which it is returned to the water jacket. Ordinarily the water tubes pass uninterruptedly from the upper to the lower header, and this may be true of the water tubes within the spirit and intent of the present invention, while, on the other hand, they may be and preferably are divided

horizontally into a plurality of horizontal sections or divisions as shown and described in our former application, Serial No. 460,403, filed October 31st, 1908. In this event the ends of the tube sections contact with the rectangular frame or frames, D, and are secured thereto, water tight, by soldering or other suitable means, the object of the frame or frames being to provide a horizontal space or passage with which all of the tubes communicate so that in case one or more of them becomes clogged or stopped up, the water may flow freely through said horizontal space or passage and reach another tube.

15 Each of the tubes preferably extends in its lateral dimensions, from front to back of the radiator and has flat sides excepting for an internal rib or ribs, S, formed on one side wall of the tube and extending to and contacting with the opposite side wall for the purpose of strengthening the tube and preventing it from collapsing. Each tube is made of a single piece of sheet metal, preferably copper, bent or doubled upon itself, as shown at c, with a sufficient curvature or sweep to leave between its two side walls a space forming a duct or passage of sufficient capacity to provide for the free passage of water, that portion of the sheet which forms one of said side walls being reflexed or bent backward upon itself as shown at c', and secured water tight, as by soldering to the other side wall. The several tubes are arranged parallel with each other and spaced apart at such distances as will leave between them passages extending from front to back of the radiator for the passage of air as the machine progresses. The adjacent ends of the several tubes are connected together by what have hereinbefore been termed "lock joints" or "lock seams" these terms being familiar and well known to those skilled in the art of sheet metal working. All of the tubes are of similar construction. The parts or features at the opposite ends of each tube, which enter into the construction of the lock joints, are made in reverse of each other so that no matter which end of a given tube is presented in a given direction its lock joint features will be similarly presented. To be more explicit and keeping in view for example, the left hand tube as shown in Fig. 8; each end of the tube has flanges F projecting laterally and in opposite direction from the side walls of the tube and each of these flanges is reflexed, or bent backward upon itself, to form a hook of substantially U-shape. The bends of the flanges which result in these U-shaped hooks are all made in the same direction with respect to the length of the tube and those on opposite sides of the tube are made in opposite directions so that the hooks at the opposite ends

on opposite sides of the tube have their free edges presented in opposite directions, while the hooks on each side of the tube have their free edges presented in the same direction. As a result of this construction, when two tubes are placed side by side, the hooks on their adjacent sides and at each end are complementary and capable of being interlocked as shown. In assembling the parts the tubes are slipped together by relative movements in directions that are longitudinal with respect to the hooks themselves, or, in other words, parallel with respect to the planes of the side walls of the tubes themselves, after which the joints are soldered making them water tight. By a similar manipulation of the parts, but in a reverse order, any one or more of the tubes may be removed for repairing, cleaning or any other purpose, the solder joints having been first opened by means of a blow pipe or the like. In addition to soldering the hooks of the lock joints together they are all soldered to the aforesaid frame or frames, D.

As ordinarily constructed the lower side of the upper header and the upper side of the lower header consist of plates and these plates have openings through which the ends of the circulating tubes pass and in which they are secured, water-tight, by solder. According to the present invention these bottom and top plates of the respective headers are not necessary because when the several tubes are assembled and their hooks are interlocked and soldered together, these hooks provide or present continuous surfaces equivalent to plates, which are adapted to contact with the frames, D, and when soldered thereto they form the bottom and top closing walls of the headers B and B' respectively. The lateral extent of the hooks is sufficient to provide between the sides of adjacent tubes ample spaces, G, for the passage of air through the radiator, horizontally, from front to back as the machine proceeds. It is desirable, however, to brace and support, laterally, the side-walls of adjacent tubes, and also to provide extended radiating surfaces. To these ends a socalled channel sheet is arranged in each of the air spaces between adjacent tubes, a perspective view of a fragment of one of these channel sheets being shown in Fig. 5 and a diagram of a fragment of the blank from which it is formed being shown in Fig. 6. This channel sheet consists of an integral sheet of copper, preferably bent rectangularly in different directions so as to form a continuous series of rectangular channels, which channels open in opposite directions, or, in other words, have their open sides, as it were, presented at opposite sides or faces of the sheet. The side walls H of the channels, the front

ends of which are flush with the front sides or edges of the tubes are common to adjacent channels and, in the illustration given in the drawings, are horizontal and divide the air spaces, G, into a vertical series of separate air passages, while the bottom walls, H², of the channels contact with the sides of adjacent tubes. These bottom walls, H², of the channels are provided with small perforations, I, one object of which is to reduce weight, while another object is to facilitate the passage of the heat from the walls of the water tubes directly into the horizontal air passages, without objectionably or seriously impairing the strength of the sheet of which the channels are formed. To this end the perforations, I, are located wholly between the bends of the sheet which result in the channels, thus leaving said bends or angular portions of the sheet intact, said perforations being formed in the blank before it is bent, as shown in Fig. 6. At their outer ends the bottoms, H², of the channels are cut away or notched as shown at I', these notches being the result of notches I' cut in the edge of the blank simultaneously with the making of the perforations and being provided principally for the sake of appearance in the completed radiator. Looking at Fig. 3, which is a section taken in a vertical plane extending from side to side of the radiator, it will be seen that at the open sides of the channels there is but one thickness of metal between the water passages and the air passages, while at the bottoms of the channels there is a double thickness of metal. If this double thickness were continued quite to the front sides or edges of the tubes, the face of the radiator would present an irregular appearance, while, on the other hand, as a result of the notches, I', the face of the radiator presents a symmetrical appearance made up of rectangular openings arranged in both horizontal and vertical alignment and having similarly aligned boundaries of uniform thickness.

It should be noted that each tube is in and of itself a complete entity. By this it is not meant that each tube is, of necessity, formed of a single or integral piece or sheet of metal, but that each is complete in itself in the sense that it may be handled and treated as an individual entity separate and apart from every other tube, and it is thus distinguished from those radiator-structures in which adjacent walls of adjacent water ducts or passages are integral or so connected that both walls of any single water duct or passage cannot be removed without at the same time removing one of the walls of each of the two adjacent water ducts or passages.

The improved radiator-structure is an extremely stout and rigid one, and the channel sheets aid very materially in resisting either vertical or horizontal strains tending to crush or collapse it.

What we claim as new and desire to secure by Letters Patent is:

1. A radiator having, in combination, two headers, a series of flat, parallel tubes connecting the headers for the passage of water, said tubes being spaced apart, leaving air passages between them, and an integral spacing, bracing and radiating sheet arranged in each of said air passages, said sheet being bent to the form of a continuous series of rectangular channels opening alternately in opposite directions, the bottom walls of said channels being in contact with the sides of adjacent tubes and being cut away or notched at their forward ends, while the side walls of said channels terminate at their forward ends flush with the front sides or edges of the tubes.

2. A radiator having, in combination, two headers, a series of flat, parallel tubes connecting the headers for the passage of water, said tubes being spaced apart, leaving air passages between them, and an integral spacing, bracing and radiating sheet arranged in each of said air passages, said sheet being bent to the form of a continuous series of rectangular channels opening alternately in opposite directions, the bottom walls of said channels being in contact with the sides of adjacent tubes and being provided with openings located wholly between the bends of the sheet which result in the channels.

3. A radiator having, in combination, headers, a plurality of tubes the opposite ends of which communicate with the headers, respectively, for the passage of water, and lock joints connecting the adjacent ends of adjacent tubes.

4. A radiator having, in combination, headers, a plurality of tubes, the opposite ends of which communicate with the headers, respectively, and U-shaped hooks projecting laterally from opposite sides of the ends of the tubes, the hooks on adjacent tubes being interlocked, forming lock joints connecting the tubes.

5. A radiator having, in combination, headers, a plurality of tubes the opposite ends of which communicate with the headers, respectively, for the passage of water, and U-shaped hooks projecting laterally from opposite sides of adjacent ends of adjacent tubes, the hooks on the adjacent sides of adjacent tubes being formed in reverse and interlocked thereby forming lock joints connecting the tubes.

6. A radiator having, in combination,

headers, a plurality of tubes the opposite ends of which communicate with the headers, respectively, for the passage of water, and U-shaped hooks projecting laterally from opposite sides of the ends of the tubes, the tubes with their hooks being of similar construction and reversible, whereby the hooks on adjacent ends of adjacent tubes may be interlocked, forming lock joints connecting adjacent tubes.
